UNITED STATES PATENT OFFICE.

JAMES F. HARTMAN, OF EAST BOSTON, MASSACHUSETTS.

FILLING-FEELER MOTION FOR LOOMS.

1,318,665.

Specification of Letters Patent. Patented Oct. 14, 1919.

Application filed November 13, 1917. Serial No. 201,774.

To all whom it may concern:

Be it known that I, JAMES F. HARTMAN, a citizen of the United States, and resident of East Boston, county of Suffolk, Commonwealth of Massachusetts, have invented an Improvement in Filling-Feeler Motions for Looms, of which the following description, in connection with the accompanying drawings, is a specification, like characters on the drawings representing like parts in each of the several views.

This invention relates to feeler mechanisms for looms operable for feeling into the shuttle during the operation of the loom to detect the substantial exhaustion of the filling and set in operation the stop mechanism of the loom and the replenishing mechanism of the filling supply. More particularly the invention has to do with a type of feeling device which might be termed "a feeler within a feeler," wherein as the main feeling member presses against the filling in the successive detecting beats of the lay, a secondary feeler member formed as a penetrating point is adapted to penetrate into the filling mass, leaving the stop mechanism normally inoperative, but such penetrating point upon the substantial exhaustion of the filling coming against the relatively hard surface of the bobbin to be pressed backward relatively to the main feeler member and thus actuate the stop mechanism. A prime object of the invention is to provide a device of this character that is certain and reliable in operation to operate the stop mechanism and being self-resetting and thus entirely automatic, the construction being also relatively simple and strong and durable in use. A further object is to provide a construction and connections of the secondary feeler or penetrating member whereby it is adapted to operate the stop motion reliably and with certainty on a very small relative movement with respect to the main feeler member whereby a smaller remnant of filling is left on the bobbin than has heretofore been the case. A further object is to provide an improved construction wherein the secondary feeler member or penetrating point may be easily and conveniently adjusted or replaced by another of different character and wherein provision is made for the quick and convenient adjustment of other working parts

to meet varying requirements. The foregoing and other objects and advantages of the invention will more fully appear from the following detailed description, and the distinctive features of novelty will be pointed out in the appended claims.

Referring to the drawings:

Figure 1 is a plan view showing a filling feeler device constructed in accordance with my invention;

Fig. 2 is a front view thereof;

Fig. 3 is an end view;

Fig. 4 is an enlarged section on the line 4—4 of Fig. 1;

Fig. 5 is a partial plan view showing the feeler elements removed; and

Fig. 6 is a transverse section on line 6—6 of Fig. 5.

The present device is mounted and carried on a bracket frame 10 which may be clamped in usual manner to the frame work of the loom by clamping devices passed through an elongated horizontal slat 11 of said bracket frame. In this frame is mounted in spaced apart bearings 12 a rock shaft 13 having applied thereto a coil spring 14 anchored at one end to the frame and at its other end to a block 15 secured to said shaft, this spring tending to turn the shaft 13 so that an angular arm 16 secured adjacent the inner end thereof is turned so that an adjustable stop bolt 17 thereon presses against a stop ledge on the frame. The shaft 13 also has fixed at its outer end an arm 18 connected to the usual stop motion of the loom. The extremity of the arm 16 projects in horizontally as seen at 16^a in position to be engaged by an oblique and somewhat concave edge 19^a of an arm 19 which is transversely pivoted at 20 to a depending lug 21 carried by the frame. The pivoted arm 19, has a lower horizontal extension 19^b adapted to rest on the frame and hold said arm normally in position so that an upper extension 19^c thereof normally extends horizontally outward. At the outer end of the frame 10 is mounted a transverse bracket plate 22 having spaced apart upright lugs 23 constituting a guide and slide bearing for the main feeler member 24, which has extending forwardly therefrom a rod 25 slidably guided in its outer end in an upstanding lug 26 of the bracket plate 22. A

compression coil spring 27 is mounted on the rod 25 and having backing against the lug 26 engages a head 24^a at the back of the main feeler member 24, pressing it yieldingly rearward so that said head comes against the lugs 23, this being the normal rearward position of the feeler. A retaining plate 28 may be secured at the top of the lugs 23 as by a screw 29 to hold the main 10 feeler member 24 from vertical displacement. In accordance with my invention a secondary feeler member formed as a small pin 30 with a pointed or knife edge extremity 30^a, is fitted to slide through the outer 15 end of the main feeler member so that the pointed extremity 30^a normally projects a little distance beyond the end of the main feeler member. The pin 30 is clamped in a 20 socket 31 of a plunger 32 slidably fitted in the main feeler member, said pin being removably held in such socket as by a small transverse clamp screw as shown, so that said pin may be easily removed and replaced by another pin having a different size or character 25 of pointed extremity, according to the varying requirements of different kinds of filling; which it will be understood vary considerably as to fineness, degree of twist and character of winding. To further facilitate 30 removal and replacement of the pin 30, the main feeler member 24 is recessed as seen at 33 adjacent its rearward end, affording a substantial finger opening so that the operator can easily reach and remove or 35 adjust the pin 30 whenever required. The plunger 32 is shouldered as seen at 32^a so as to limit the rearward movement thereof and it is yieldingly pressed rearward by a coil spring 34 encircling a rod projecting from 40 the front of said plunger and reacting against an abutment of the main feeler which also serves as a forward guide for said rod; the front portion of the main feeler member being recessed as seen at 35 45 to afford room for the housing of said spring and for the operation of the secondary feeler plunger 32. The plunger 32 has operatively engaged therewith as seen at 36 the upper portion of a pin 37 rigid with and 50 extending upward from a short shaft 38 transversely journaled in spaced apart lugs 39 depending from the main feeler member. The shaft 38 also has fixed at an outer projecting end thereof an upright plate arm 40, 55 the upper end of which is notched as seen at 41. Coöoperating with this plate and guided in the notch 41 is a trigger plate 42 rigid with and carried by an arm 43 which is pivoted at 44 to the head 24^a at the front of the main feeler member, the arm 43 being a 60 two-part construction with an interposed adjusting turn buckle 45 equipped with a clamp nut 46 whereby said arm may be adjusted as to length as required for its proper operation. The trigger plate 42 has its

outer portion formed with a ledge 42^a adapted to rest on and be supported by the plate arm 40 engaging the same at the bottom of the notch 41. Just back of the ledge 42^a the trigger 42 is formed with a relatively deep notch 42^b permitting said trigger and the arm 43 to drop some little distance when the arm 40 is swung slightly to disengage the ledge 42^a from the bottom of the notch 41 so that said trigger will then come to rest 75 with the bottom of the notch 42^b thereof engaging the bottom of the notch 41. A spring 47 anchored to the head of the back of the main feeler at 48 presses on the forward portion of the arm 43 to hold the ledge 80 42^a normally pressed against the arm 40 and to accelerate the downward movement of the arm 43 when said trigger is tripped. The arm 43 has a downward extension 43^a with spaced apart inward projections 43^b, 85 43^c adjacent its lower end adapted to receive and hold between them the end of the arm extension 19^a when the arm 43 drops downward as described; the depth of the notch 42^b being such as to position said projections correctly for this purpose. 90

It may now be understood that in the normal operation of the loom the trigger 42 will be cocked, *i. e.*, with the ledge 42^a resting on the arm 40, and the penetrating point 30^a will be yieldingly held projected a small distance from the end of the main feeler member so that on the detecting beats of the lay, as the main feeler member passes through the slot S' of the shuttle S, said penetrating point will press into the filling so that the main feeler member 24 will be pressed back without any relative movement of the plunger 32 with respect thereto. As soon, however, as the filling becomes substantially exhausted the penetrating point 30^a coming against the relatively hard surface of the bobbin will be pressed inward on the detecting beat and this small movement transmitted through the relatively short arm 37 will turn the shaft 38 and swing the arm 40 so that the ledge 42^a of the trigger 42 will drop off the arm 40 and permit the arm 43 to swing downward. The lower end of the arm 43^a which has normally been held above the 110 arm extension 19^a so as to clear the same, is now positioned so that the end of said arm extension comes between the projections 43^b, 43^c, thus as the main feeler member is pressed backward swinging the arm 19 upward and causing oblique concave edge 19^a thereof to act as a cam swinging the arm extension 16^a laterally and thus rocking the shaft 13 to operate the stop motion. The arm 43^a which thus engages the arm 19 to 115 lift it, is itself lifted as the main feeler member moves backward, so that the ledge 42^a of the trigger is again lifted over the bottom of the notch 41^a in arm 40, whereupon the spring 34 again presses the pen- 120

trating point forward, and swings the arm 40 back to engage under the ledge 42^a, thus automatically resetting the device for another operation. It will be observed that the 5 stop motion in this way is not set in operation immediately on the pressing back of the penetrating point 30^a with respect to the main feeler, but that the main feeler is pressed back on this movement, and another 10 full movement of the lay takes place before the arm 19 is lifted to operate the stop motion. Hence in practice, three picks are obtained after the point 30^a is pressed back on impinging the bobbin core, thus permitting 15 that much more of the filling to be removed before the bobbin is extracted. It is to be noted that with the described construction only a very small pressing back of the point 30^a is necessary to operate the stop mechanism,—*i. e.*, just enough so that when multiplied by the lever connections described, the arm 40 will be pushed off the ledge 42^a, it being understood that it only rests on a small corner of said ledge when in cocked 20 position. Thus the end of the main feeler may approach relatively very close to the bobbin core, *i. e.*, removing all but a minimum layer or so of thread before the point 30^a is pressed back to operate the stop. In 25 this way also the end of the main feeler member 24 may slip over the yarn with the penetrating point 30^a offering a minimum of obstruction by reason of its relatively minute projection into the filling mass. The described construction and arrangement of the 30 oscillating shaft 13 with the arm 19 will be recognized as pertaining to the well known Stafford loom type. For applying the invention to a loom of the Draper or similar type the arm 19 is equipped with an up- 35 standing projection 49 which is adapted to coöperate with the stop mechanism of the Draper loom in a manner that will be readily understood. I am aware that the invention may be embodied in other specific 40 forms without departing from the spirit or essential attributes thereof, and I therefore desire the present embodiment to be considered in all respects as illustrative and not 45 restrictive, reference being had to the appended claims rather than to the foregoing 50 description to indicate the scope of the invention.

Having described my invention, what I 55 claim as new and desire to secure by Letters Patent is:

1. In a loom, the combination with a stop motion operating element, of a spring 60 pressed feeler carrying member normally clearing said element, but equipped to move automatically into the path thereof when released, a trigger for holding said member in inoperative position to clear said element, and a secondary spring pressed feeler 65 presenting a penetrating point to project

beyond the main feeler having connections to trip said trigger and release said member for movement upon pressing back thereof.

2. In a loom, the combination with a stop motion operating element, of a spring 70 pressed feeler carrying a member normally clearing said element, but equipped to move automatically into the path thereof when released, a trigger for holding said member in inoperative position to clear said element, and a secondary spring pressed feeler presenting a penetrating point to project beyond the main feeler having motion multiplying connections to trip said trigger and release said member for movement upon 75 pressing back thereof, said member being biased to then move for engaging said motion operating element.

3. In a loom, the combination with a stop motion operating element, of a spring 80 pressed feeler carrying a member normally clearing said element but biased to move automatically into engagement therewith when released, a trigger presenting a ledge for holding said member in inoperative position to clear said element, and a secondary spring pressed feeler presenting a penetrating point to project beyond the main feeler and having motion multiplying connections 85 to trip said trigger and release said member for movement upon pressing back of 90 said point.

4. In a loom, the combination with a stop motion operating element, of a spring 95 pressed feeler carrying a member normally clearing said element but biased to move automatically into engagement therewith when released, a trigger presenting a ledge for holding said member in inoperative position to clear said element, a secondary 100 spring pressed feeler presenting a penetrating point to project beyond the main feeler and having motion multiplying connections to trip said trigger upon pressing back of said point, and means for automatically resetting said trigger after it is tripped to place it in readiness for another operation.

5. In a loom, the combination with a stop motion operating element, of a spring 115 pressed feeler carrying a member normally clearing said element but biased to move automatically into engagement therewith when released, and means for causing the operation of said member to engage said element 120 including a secondary spring pressed feeler presenting a penetrating point to project beyond the main feeler, said secondary feeler having a removable fitting permitting its replacement by another for the purpose stated.

6. In a loom, the combination with a stop motion operating element, of a spring 125 pressed feeler carrying a member normally clearing said element, but equipped to move

automatically into the path thereof when released, a trigger for holding said member in inoperative position to clear said element, and a secondary spring pressed feeler presenting a penetrating point to project beyond the main feeler having connections to trip said trigger upon pressing back there-

of, said secondary feeler having a removable fitting permitting it to be replaced by another with a different type of penetrating point.

In testimony whereof I have signed my name to this specification.

JAMES F. HARTMAN.
